UNITED STATES PATENT OFFICE

CHARLES S. CHRISMAN, OF WEST CHESTER, PENNSYLVANIA, ASSIGNOR TO THE U. G. I. CONTRACTING COMPANY, OF PHILADELPHIA, PENNSYLVANIA, A CORPORATION OF DELAWARE

VERTICAL FIRE TUBE BOILER

Application filed December 10, 1926. Serial No. 153,754.

Objects of the present invention are to provide a vertical fire tube boiler adapted not only for direct firing but also for use as a waste heat boiler; to increase the rapidity of circulation of water in the boiler while securing to a large extent counterflow of the water and heating gases increasing thereby the efficiency of heat transfer; to eliminate the necessity of a separate steam drum and its water and steam connections; to complete the combustion of the heating gases, when necessary, and to reduce the temperature of the gases before their impingement upon the lower tube sheet; to avoid danger of burning the tube sheets; to recover heat alternately from gases of different types as from a waste gas and a gas other than waste; to, in the case of gases of a carbureted water gas set, efficiently recover heat in the waste blast gases and to recover a considerable portion of the heat in the carbureted water gas without passing the carbureted water gas through the tubes, thus obviating fouling them by tar; to reduce the temperature of carbureted water gas as low as possible without deposition of tar before it reaches valves and other parts of apparatus to which it is delivered for condensing; and to minimize the danger of dust and other impurities being carried up through the tubes.

Other objects of the invention will appear from the following description at the end of which the invention will be claimed.

The invention may be said to comprise a vertical fire tube boiler provided at the top with a feed water inlet and having a cylindrical wall arranged in the water space and spaced from the boiler shell to provide an annular space, said annular space accommodating the upward peripheral flow of hot water, a boiler setting spaced from the boiler shell and providing a chamber, and means for passing hot gases down through the chamber and up through the tubes in counterflow relation with the water, with or without means for passing other hot gases down through the chamber in counterflow relation with the water in said annular space and bypassing the tubes out of said chamber.

The invention also comprises the improve-

ments to be presently described and finally claimed.

In the following description reference will be made to the accompanying drawings forming part hereof and in which

Figure 1 is an elevational view in section of a vertical fire tube boiler embodying features of the invention and arranged for operation with gases of two kinds or character.

Fig. 2 is a transverse sectional view taken on the line 2—2 of Fig. 1.

Fig. 3 is an elevational view, partly in section, illustrating a modification of the invention showing the boiler arranged for operation with one kind of hot gas and direct firing.

Fig. 4 is an elevational view, partly in section, illustrating a modification in which two of the boilers are associated in the setting.

Fig. 5 is a horizontal sectional view taken on the line 5—5 of Fig. 4, and

Fig. 6 is a transverse sectional view taken on the line 6—6 of Fig. 4.

Referring more particularly to Fig. 1, the vertical fire tube boiler is shown as provided with top and bottom tube sheets 1 and 2 associated with the fire tubes 3. At the top there is a feed water inlet 4 shown to include a feed water heating coil 5 and extending axially into the boiler to substantially the water level. 6 is a cylindrical wall arranged in the boiler between its shell and tubes and spaced from the boiler shell to provide an annular space 7. The wall 6 extends from substantially the water level to a point above the lower tube sheet 2. The annular space 7 accommodates the upward peripheral flow of hot water. 8 is a boiler setting spaced from the boiler shell and it provides a chamber 9 around the water space of the boiler and the lower tube sheet 2. There are means for passing hot gas down through the chamber 9 and up through the tubes in counterflow relation with the water. The construction illustrated in Fig. 1 is adapted for use at different times with two kinds of gases, for instance blast gas and carbureted water gas from a carbureted water gas set, and in that case the hot gas, either blast gas or carbureted water gas, is admitted at 10 and

descends through the chamber 9, as indicated by both the dotted line arrows and the full line arrows. In the case of the blast gas it is passed up through the tubes 3, as indicated by the full line arrows, in counterflow relation with the water. For this purpose the valve at the offtake 11 is closed and the valve at the offtake 12 is open. The carbureted water gas by-passes the tubes 3, as indicated by the dotted line arrows, and for this purpose the valve 12 is closed and the valve 11 is open. In the particular application of the invention under discussion, it is an advantage to have the carbureted water gas by-pass the tubes because if it passes through the tubes there is danger of deposition of tar on the surface of the tubes which receiving dust from the subsequent passage of blast gas produces an objectionable coating or deposit. Inasmuch as the direction of flow of the gas that passes through the tubes is changed at the bottom of the boiler, there is a tendency for dust to fall out of the gas, and the hopper 13 at the base of the setting may well be provided for the reception and removal of such dust. The lining of the setting forms a contraction or throat as at 14 which operates to impart a swirling motion to the gases as they descend through the chamber 9. 15 is a ring or collar, shown as corrugated, at the top of the chamber 9, and it serves to protect the shell of the boiler from erosion by the entering gas or, perhaps more accurately, by dust carried along with the gas. 16 is a steam offtake from the boiler. 17 is a mud drum arranged outside of the boiler setting and connected by a pipe 18 with the water space of the boiler and provided with a blow off fitting 19. 20, Figs. 1 and 2, are jet tubes arranged to discharge tangentially into the lower part of the water space of the boiler to insure the movement of mud to the pipe 18. The open ended tube 21 around which the feed water heater coil 5 is wound serves to deflect the gas in its travel through the chamber 22 of the feed water heater in the manner indicated by the full line arrows, thus providing a counterflow between the feed water and the gas in the feed water heater. The construction and mode of operation of the modification of the invention illustrated in Fig. 3 are as has been described with the exception that the setting 23 is modified to provide a combustion chamber 24 from which hot gases or products enter the annular chamber 9^a by way of the opening 25. In this modification the passage of the hot gas is indicated by full line arrows. The construction and mode of operation of the modification illustrated in Figs. 4 to 6 are as has been described except as follows: Two boilers 26 and 27 each of the type illustrated in Fig. 1 and above fully described are mounted in a single setting 28, and these boil-

ers have gas and steam offtakes 30 in common. In order to circulate the gas in the chambers 9^c there is shown a baffle 31, and it may be remarked that the gas entering at 32 does not impinge upon either of the boilers but is diverted by a projection 33 to each of the boilers. In application to the manufacture of carbureted water gas the blast gas enters at 32, descends through the chamber 9^c, and rises through the tubes of the boiler and through the feed water heater and out at the offtake 29. The valve 34 is closed. Carbureted water gas follows the same path but by-passes the boiler tubes because the valve at 29 is closed and because the valve that controls the outlet 34 is open.

It will be obvious to those skilled in the art to which the invention relates that modifications may be made in details of construction and arrangement and matters of mere form without departing from the spirit of the invention which is not limited to such matters or otherwise than the prior art and the appended claim may require.

I claim:

A fire tube boiler, adapted to be heated alternatively by two kinds of gases one of which is injurious to the tubes of the boiler, comprising in combination, a vertical cylindrical boiler shell, a boiler setting surrounding said boiler shell and spaced therefrom to form a gas passage, a gas inlet to said passage near the top of the setting, a smoke box above the top of said boiler shell, a gas chamber below said shell in communication with said gas passage, a plurality of vertical fire tubes extending through said shell connecting the smoke box with said gas chamber, means for withdrawing the injurious gas from the gas chamber and offtake means for the other gases from said smoke box.

CHARLES S. CHRISMAN.
